(57) **CLAIM**

The ornamental design for an archery bow riser, as shown and described.

DESCRIPTION

FIG. 1 is a left side view of an archery bow riser, which forms a part of an archery bow. A right side view of the claimed portions of the archery bow riser would be a mirror image of the claimed portions of FIG. 1.

FIG. 2 is a rear view of the archery bow riser of FIG. 1; and, FIG. 3 is a perspective view of the archery bow riser of FIG. 1.

The broken lines immediately adjacent to the solid lines of the archery bow riser in the handle/grip area and in the upper and lower areas of the riser in FIGS. 1-3 form the boundary of the claim, with the broken lines themselves forming no part of the claimed design. The broken lines showing the limbs, rotatable members, cable positioning devices and the rest of the riser are included for the purpose of illustrating environment and do not form a part of the claimed design.

1 Claim, 3 Drawing Sheets
